United States Patent Office.

MYRTILLUS A. CRAVATH AND ISAAC M. CRAVATH, OF BLOOMINGTON,
ILLINOIS.

Letters Patent No. 96,205, dated October 26, 1869; antedated October 16, 1869.

IMPROVED SNOW-PLOW.

The Schedule referred to in these Letters Patent and making part of the same.

To whom it may concern:

Be it known that we, MYRTILLUS A. CRAVATH and ISAAC M. CRAVATH, of the city of Bloomington, county of McLean, State of Illinois, have invented new and useful Improvements in Snow-Plows; and we do hereby declare that the following is a full, clear, and exact description of the construction and operation of the same, reference being had to the drawings, in Nos. 1 and 2, making a part of these specifications, in which—

No. 1 is a perspective view.

No. 2, Figure 1, is a top view with part of head-block cut away, showing the revolving plow, for which Letters Patent were granted, July 16, 1867, No. 66,802.

Figure 2 is a side elevation, inside view.

Figure 3 is a top view of rack and pinion.

Figure 4 is a front view of revolving plow.

The frame A is constructed with a head-block, corresponding to the head-block of the locomotive, to which it is attached by means of bolts, and with a foot-block, which is attached to the locomotive by means of braces.

Two uprights are framed through the head-block and foot-block, in such position that the horizontal screw F, at the top, and the inside bearings of revolving plows, D D, at the foot, are received.

The mould-boards B B and C C are mitred at the point, and shaped like those in common use, and are fastened to arms of unequal lengths by means of bolts at the points.

The mould-boards B B are fastened to short arm H by means of curved brace d.

The mould-boards C C are cut off near the point, and are fastened to long arm I by means of hinged joint K. The mould-boards C C are longer than mould-boards B B, projecting forward on either side; they are also raised above them, so that the share or cutting-edge is nearly level with the top of mould-boards B B. The rear of said mould-boards is attached to long arm I by means of curved braces J J.

The arms H and I are keyed to upright E. Said arms are coupled together by means of coupling-brace b, and are also attached to said upright by means of brace c.

The curved braces J J are each provided with a rack, which meshes into and is operated by pinion L. Said rack and pinion are confined to arm I by means

of clamp j, and operated by hand-wheel f on shaft g, said shaft being held in position by step in arm I, and passing through clamp j and brace e.

A worm-pinion, G, is attached to the top of upright E, and operated by horizontal screw F, for the purpose of switching the points of the plows to either side, and holding them in any desired position.

The plows, thus constructed, are hinged to frame A by means of two journal-boxes, a a, one attached to the front of the head-block, and the other to the front of the foot-block, by means of bolts. The revolving plows D D are attached to frame A at an angle of about twenty degrees, and in such position as to bring the convex sides near the rails on the inside, and so as to project below the surface of the rails sufficiently to clear the grooves and prevent the locomotive from leaving the track.

The operation is as follows:

The operator stands on the platform, made by coupling the head-block of the plow with the head-block of the locomotive. The plows are placed with the points at equal distances from the rails. The curved braces J J are expanded, and a spring-pin, o, is inserted. In case of a high bank on one side of the track, the snow may all be thrown on the opposite side by switching the points of the plows toward the bank, by means of the hand-screw F, until the curved brace J is brought against the rest p. In running into a station, or when desired, the mould-boards C C are drawn in, by means of the rack and pinion L, as shown by dotted lines. The foot of the operator is placed on the spring-pin o, and the hand on the wheel f.

We claim—

1. The construction and arrangement of mould-boards, with hinged joints near the point, and with rack and pinion for operating the same, in the manner and for the purpose herein described.

2. The construction and arrangement of plows with horizontal arms H and I, upright shaft E, journal-boxes a a, worm-pinion G, and horizontal screw F, for operating the same, in the manner and for the purpose herein described.

MYRTILLUS A. CRAVATH.
ISAAC M. CRAVATH.
